UNITED STATES PATENT OFFICE.

ISRAEL GILSEY, OF CINCINNATI, OHIO.

DISPLAY-STICK.

No. 833,320.

Specification of Letters Patent.

Patented Oct. 16, 1906.

Application filed April 25, 1906. Serial No. 313,631.

To all whom it may concern:

Be it known that I, ISRAEL GILSEY, a citizen of the United States of America, and a resident of Cincinnati, county of Hamilton, 5 State of Ohio, have invented certain new and useful Improvements in Display-Sticks, of which the following is a specification.

The object of my invention is a display-stick which in its closed position presents the 10 appearance of an ordinary stick, such as that of a walking-stick, but which is provided with a means operated by actuating a button for projecting from its top a rod to which a flag is attached, the flag in the operation unfurling automatically.

In the accompanying drawings I have illustrated a display-stick embodying my invention.

Figure 1 is a side elevation of a stick with 20 the rod in its extended position and the flag unfurled. Fig. 2 is a side elevation of the stick in its closed position. Fig. 3 is a sectional view, upon an enlarged scale, of the stick and a partial view of the rod and flag, 25 the central part of the stick being broken out and the ends being brought together to economize space. Fig. 4 is a detail perspective view of the knob, showing the rod and the flag in the position they occupy when closed.

Referring to the parts, the stick A has a 30 central longitudinal bore a. Near the lower end of the bore a a slot a' is cut in the stick extending into the bore. Adjacent to the slot a' a leaf-spring B is attached, from the 35 upper loose end of which a finger b projects in through slot a', the outer end of the finger terminating in a button b'. To the upper end of the stick A a hollow spherical knob C is secured, the upper end c of the knob being 40 open and having a cap c' attached to it by means of a hinge c². Within the bore a a straight longitudinal rod D is situated, the lower end of which terminates in a tooth d, which is beveled upon its lower end to press 45 the dog b outward when the rod is pushed downward and has a shoulder upon its upper face to engage dog b to hold the rod in its lowermost position. A coiled spring E is secured to the end of the rod adjacent to the 50 tooth d, the upper end of the spring E being secured to the top of stick A adjacent to the bore a, the tendency of the spring being to contract and exert a normal outward pressure upon the rod D. Secured to the outer

end d' of the rod D is a tape F, the other end f 55 of which is secured to the top of the stick A within the knob C. To tape F at intervals a series of rings f' are secured which are fitted over the rod D. To the upper part of the tape F the side of a flag G is secured. The 60 tape F is made of a length such that it will permit the spring E to project the rod D above the top of the knob C a distance such as to carry the flag G clear above the top of the knob.

When the rod D is depressed so that the tooth d is engaged by dog b, the upper end d' of the rod is in the bottom of the knob, the tape F is folded likewise in the bottom of the knob, the eyelets f' are brought together 70 near the upper end of the rod, and the flag G is folded together within the interior of the knob, whose cap c' may then be placed in its closed position. Now if the button b' be drawn outward, releasing the tooth d, spring 75 E immediately shoots rod D upward, which will throw the cap c' open and shoot forward until it is stopped by the tape F, which, being straightened out, itself stretches the flag F and presents it in an unfurled position, such 80 as shown in Fig. 1.

What I claim is—

1. The combination of a stick having a hollow bore in its upper end, a hollow knob secured upon the top of the stick, a rod with- 85 in the bore, a spring for pressing the rod normally outward, a catch within the bore for holding the rod in its retracted position, a tape secured to the upper end of the rod and to the knob to limit the outward movement 90 of the rod, and a strip of flexible fabric secured to the upper end of the tape.

2. The combination of a stick having a hollow bore in its upper end, a hollow knob secured upon the top of the stick, a rod with- 95 in the bore, a spring for pressing the rod normally outward, a catch within the bore for holding the rod in its retracted position, a tape secured to the upper end of the rod and to the knob to limit the outward movement 100 of the rod, a series of rings secured to the tape near its upper end and surrounding the rod and a flag secured to the upper end of the tape adjacent to the rings.

ISRAEL GILSEY.
